United States Patent Office

DAVID H. BALL, OF SINNAMAHONING, PENNSYLVANIA.

Letters Patent No. 78,508, dated June 2, 1868.

IMPROVEMENT IN SHINGLE-MACHINES.

The Schedule referred to in these Letters Patent and making part of the same.

TO ALL WHOM IT MAY CONCERN:

Be it known that I, DAVID H. BALL, of Sinnamahoning, in the county of Cameron, and State of Pennsylvania, have invented certain new and useful Improvements in Shingle-Sawing Machines; and I do hereby declare the following to be a full, clear, and exact description of the same, reference being had to the accompanying drawings, making a part of this specification, in which—

Figure 1 is a plan view of a sawing-machine, constructed with my improvements attached.

Figure 2 is a sectional view of the same, on the line XX.

Figure 3 is a sectional view of the same, on the line YY.

Figure 4 is a view of one side of the machine.

Figure 5 is a perspective representation of the guide, marked I I', in fig. 1.

Figure 6 is an end view of the carriage, marked K, in fig. 1.

The nature of my improvements has reference to several distinct parts of a shingle-sawing machine, the construction and operation of which are clearly set forth in the following detailed description.

In the drawings, the parts marked A A A constitute the main frame of the machine. A¹ is a centre partition, running lengthwise of said frame, and A² is a small square frame adjoining.

B is the saw-shaft, running across the large and small frames A A². B¹ is the circular saw, and B² is a belt-pulley on the saw-shaft, to which the power is applied. B³ is a fly-wheel, on the same shaft, opposite the pulley, and revolving within the small frame A².

C C' are alternate speed-cones, connected by a belt, C''. The cone C is journalled within the frame A, on the same shaft with which is a belt-pulley, c, connected by belt a with the saw-shaft. The other cone is journalled in boxes d' d, attached to the top of the frame A and centre partition A¹.

d² represents a pinion, on the shaft of cone C', gearing with a larger tooth-wheel, d³, on the crank-shaft d', said crank-shaft revolving in boxes e d.

The box d' is provided with slots f f, so that by moving it, the wheels d² d³ may be geared and ungeared at pleasure, which is done by means of the rod G, connected with the box d', thence passing, as shown, to the opposite end of the frame, where it is attached to a single or double lever, G¹, working in the frame A.

H is a slanting block, below the alternate cones, provided with a hollow screw, h', in the block, or in a box inserted therein, and operated by crank-screw H', turned from the outside of the frame. This crank-screw rests within the frame, as clearly shown in the drawings. The said block is also provided with arms h h h, on both sides thereof, which extend upwards on both sides of the belt C'', and which act as regulators thereof, movement to either side being obtained by turning the crank-screw.

The parts marked I I' constitute a saw-guide, the ends and centre of which rest in suitable recesses in the frame A and centre partition A¹. i i' are curved arms, the ends of which touch the sides of the saw. i² is a circular opening, between the said arms, within which the saw-teeth pass.

j is a slot, through one end of the guide, within which is a bolt, j', and by which the guide is bolted to the frame. A recess, j'', is cut in the frame, to admit the insertion or withdrawal of the bolt. m m are keys, tightening the ends of the guide in their position. The saw is guided by driving the guide from either side of the frame A. The guide is constructed in two parts, I and I', in order that the smaller part I' may be driven separately against the saw, as the wear on the end of the arm i may necessitate.

K represents the carriage, upon which the block to be sawed is placed. k k are the end braces of the carriage, somewhat thicker than the carriage, and provided with grooves k' k', clearly shown in fig. 6. The carriage slides on round metal bars n n n n, running lengthwise of the main frame A and partition A¹, to which they are attached, by curving their ends downwards, and inserting them in the frame and partition, or in any other suitable manner, so as to leave the part of the bars upon which the carriage slides above and free therefrom.

n' n' are metal plates, on the under side of the braces k k, to prevent any other than the desired move-

ment to the carriage. A roller, L, is placed in the main frame A, upon which the carriage moves, preventing strain, and reducing friction, as seen in fig. 2.

o o o are metal plates, bolted across the upper face of the carriage K. p represents the head-block, to which are attached the dogs p' p''. The dogs are so constructed as to rest, as shown in drawings, and slide on the metal plates o o o, by which they are prevented from springing.

P P are slides for the head-block, which, with the head-block and set-works, are constructed upon the same principle as those of most shingle-sawing machines with horizontal feed. The head-block on my machine, however, extends far enough to each side as to permit of the use of set-racks p'' p''' in two positions on each side of the head-block; the racks being adjusted on the inner knobs q q, for short shingles, and on the outer knobs q' q' for long shingles; the set-rod r being provided with an extra pair of set-buttons, r' r''. The racks used in sawing short shingles may have fine teeth, while those for long shingles may have coarse teeth. t t t are curved standards, holding the racks P'' P''' in position. The racks may be removed by moving the head-block forward, and releasing the racks from the knob q q'.

On one end of the set-rod r a square block, s, or nut is shown, against which rests a spring, s', attached to the carriage K. When the set-rod is not in motion, a flat surface or edge of the block is at all times presented to the spring, which presses against it. This block is so arranged, in reference to the set-block s'' and set-buttons r r', that after each distinct movement of the head-block, the buttons r r' and set-block s'' will be in the proper position to receive another; the buttons, when not actually operating on the racks, being entirely free therefrom.

The carriage K connects with the crank-shaft d', by means of a pitman, k³, and crank d'.

What I claim as my invention, and desire to secure by Letters Patent, is—

1. The plates o o, when arranged in relation to the head-block p, and dog p' p'', said dogs being constructed to rest or slide on the plates, as and for the purpose specified.
2. The block s, and spring s', constructed and arranged to operate as and for the purpose set forth.

D. H. BALL.
